UNITED STATES PATENT OFFICE.

ISAIAK YABLON AND CHARLES WEIS, OF LANCASTER, PENNSYLVANIA.

SKIRT-SUPPORTER.

1,311,852.

Specification of Letters Patent. Patented July 29, 1919.

Application filed August 23, 1918. Serial No. 251,153.

To all whom it may concern:

Be it known that we, ISAIAK YABLON and CHARLES WEIS, citizens of Russia and the United States, respectively, residing at 566 5 Rockland St. and 534 Park Ave., respectively, Lancaster, in the county of Lancaster and State of Pennsylvania, have invented new and useful Improvements in Skirt-Supporters, of which the following is a specification.

The invention relates to apparel and more particularly to a garment supporter, and has for an object to provide a skirt or garment supporter for use in supporting a garment 15 at the waistline.

The invention comprehends among other features the provision of a device that can be readily arranged in position around the waistline of the wearer, and which can be 20 easily adjusted for different sizes of waistlines, the device when in position permitting of readily arranging the skirt so that the same will be properly supported relative to the body of the wearer.

It is well known that various forms of 25 garment supporters have been used heretofore, but in many of these cases the supporters are expensive to manufacture; are clumsy in appearance and hard to apply, 30 and furthermore, cannot readily be adjusted to fit the different waistlines. Still further the garment supporters in many instances are not efficient and do not properly perform the function for which they are intended. With our invention we aim to 35 provide a skirt supporter that can be cheaply manufactured, and which involves novel features of construction and arrangement, whereby the supporter can be readily accommodated to different waistlines.

In the further disclosure of the invention, reference is to be had to the accompanying drawing, constituting a part of this specification, in which similar characters of reference 45 denote corresponding parts in all the views, and in which—

Figure 1 is a front elevation of the skirt supporter as applied without the skirt being shown.

Fig. 2 is a rear elevation.

Fig. 3 is a side view.

Fig. 4 is a fragmentary vertical sectional view taken on the line 4—4 in Fig. 2, and

Fig. 5 is a fragmentary sectional view 55 showing the manner of supporting the skirt.

Referring more particularly to the views,

the skirt supporter in its entirety is indicated by the numeral 10, and consists substantially of two similar sections 11, each adapted to partially encircle the waist around the sides 60 thereof. Each section is formed of a central horizontal band 12, and upper and lower bands 13 and 14, the latter being preferably elastic, although it is not absolutely necessary that they be so. The bands 12, 13 and 14 are connected by uprights 15 and 16, of which the uprights 15 are the end uprights, and the uprights 16 intermediates, the uprights being formed of flexible material such as steel or boning, and of course covered 70 with material, as shown. The band 12 of one of the sections has an extension 17 at the front to connect with a buckle 18 on the front end of the band of the other section. So also the band 12 of the first-mentioned 75 section has an extension 19 at the rear which passes loosely through a loop 20 on the rear upright of the other section, and is provided with an adjustable clasp 21 arranged to slide upon the central band of the other 80 section, thus providing for an increase or decrease in the length of the extension 19 relative to the other said section. So also the lower band 14 on the first-mentioned section has an extension 22 passing through a 85 loop 23 on the end upright of the other section and carries a clasp 24 mounted to slide on the lower band of the said other section, so as to provide a similar adjustment of the lower band of the sections. 90

It will be seen that when the device is applied around the waist of the wearer, the lower band will adjust itself to conform to the structure of the wearer immediately below the waist, and the central band will substantially encircle the waistline, so that sections will be at the sides of the waist and the extensions of the bands at the front and rear. A skirt indicated by the numeral 25 has an inside band 26 attached to the upper part of the 100 skirt, so that the upper band 13 will be arranged within the skirt to bear against the inside band 26 thereof, and thus the skirt will be held snugly in place, and by having the same evenly held at the sides, the skirt 105 will hang properly and not be distorted in shape.

It will be seen by reference to the views, that the uprights will not necessarily remain straight, but will curve to conform to the 110 curvature of the waistline, and thus it will be apparent that with a device of the char-

acter described, the same can be readily buckled around the person and secured in position to support the skirt, without presenting a clumsy appearance or being uncomfortable to the wearer.

From the foregoing description, it will also be apparent that the device described can be cheaply manufactured, particularly in view of the fact that it need not necessarily be made to certain sizes, but can be adjusted to readily fit the waistline of almost any person.

We claim:

A skirt supporter comprising a plurality of similar connected sections, each consisting of a centrally arranged horizontal band, an upper horizontal band, a lower horizontal band, uprights connecting said central, upper and lower bands, a front extension formed by the front end of the central band of one of the sections, a similar front ex-

tension formed by the front end of the central band of the other section, a buckle on one of said extensions for connection with the other extension, a rear extension formed by the rear end of the central band of one of the sections, a loop on the rearmost upright of the other section and having the rear extension loosely passed therethrough and a clasp slideable on the central band of the other section and connected to the rear extension beyond the loop, an extension formed by the end of the lower band of one of the sections, a loop on the rearmost upright of the other section and a clasp on said last mentioned extension and having sliding engagement with the lower band of the other section beyond the last mentioned loop.

In testimony whereof we affix our signatures.

I. YABLON.
CHARLES WEIS.
